C. W. LEWIS

PORTABLE MERCHANDISING CASE

Filed June 18, 1923

UNITED STATES PATENT OFFICE.

C. WELLINGTON LEWIS, OF GLENSIDE, PENNSYLVANIA, ASSIGNOR TO L. H. GILMER CO., OF PHILADELPHIA, PENNSYLVANIA, A CORPORATION OF NEW JERSEY.

PORTABLE MERCHANDISING CASE.

Application filed June 18, 1923. Serial No. 646,253.

My invention is an improved merchandising case particularly designed for use in the retailing of merchandise. To satisfactorily effect the retail distribution of such merchandise as automobile fan belts, it is essential that the dealer carry in stock a comprehensive assortment of belts adequate to meet the requirements of a large number of different makes and models of automobiles, and that such stock be immediately accessible and yet protected from pilferage. My invention is designed to provide a convenient, attractive and inexpensive counter case having compartments of varying lengths for the accommodation of the different size cartons necessary for the storage of an adequate supply of belts; which is readily accessible from the rear of the counter only; which has walls affording a satisfactory foundation for the displaying of advertising matter exploiting the contained product; and which deprives the dealer of the use of but little counter space. In its preferred form, my invention comprises a frame consisting of base members having fixed thereto parallel vertical uprights which support a top of smaller area than the base. A plurality of spaced horizontal partitions, supported by the frame, form compartments of suitable height which are enclosed by sheathing walls of sheet material fixed to the frame and having overlapping flanges whereby the parts are held together. The end wall of the case is inclined to the vertical and the compartments formed in the case are consequently of gradually increasing length from the top to the bottom of the case, such inclined wall being preferably held rigid by attachment to oblique edges of the frame uprights.

The characteristic features of my invention will more fully appear from the following description and the accompanying drawings in illustration of a preferred embodiment of my improvements.

In the drawings, Fig. 1 is a vertical sectional view of a portable merchandise case embodying my invention; Fig. 2 is a fragmentary sectional view taken on the line

2-2 of Fig. 1; Fig. 3 is a perspective front-side view of my improved case; and Fig. 4 is a perspective rear-side view of my improved case, showing cartons therein.

As illustrated in the drawings, base members 1 have fixed thereto pairs of similar uprights 2 and 3 which support a top piece 4 of smaller area than the base. The uprights 2 preferably have vertical edges and the uprights 3 preferably have diagonal or oblique front edges 3'. Partitions 5, preferably of sheet metal, are engaged in slots 6 formed by saw kerfs in the uprights, the partitions being provided with reinforcing flanges 5' and 5''. Side walls 7, of sheet material, are fixed to the frame and provided with flanges 7' overlapping the ends of slots 6 and the partitions 5 engaged therein to prevent the withdrawal of such partitions. An inclined front wall 8 is fixed to the frame along the diagonal edges 3' of the uprights 3 and is provided with flanges 8' which overlap the oblique edges of the side walls 7. A cover 9, fixed to the top piece 4, is provided with peripheral flanges 9' which overlap the side and end walls and the flanges 7'.

For convenience of manufacture the frame members are preferably made of wood and the sheathing walls of sheet metal.

A case so formed will hold in compact and accessible relation a large number of cartons of different lengths, thereby enabling the dealer to maintain complete stocks without dispersion thereof. The sheathing walls of the case may be inscribed with suitable pictorial or other advertising matter making an attractive counter display and the top of the case may be used as a shelf for the display of other merchandise, thereby minimizing the loss of valuable counter space.

Having described my invention, I claim:

1. A portable merchandising case comprising a frame having a top, bottom and side members, horizontal partitions connected with said side members, and a sheathing of sheet material for said frame and comprising side walls having flanges en-

gaging edges of said partitions to prevent removal thereof from said side members.

2. A merchandising case comprising a frame, a plurality of horizontal partitions carried by said frame, and a sheathing for said frame comprising side walls provided with flanges overlapping edges of said par-

titions, an inclined end wall having flanges overlapping edges of said side walls, and a cover having flanges overlapping edges of 10 said side and end walls.

In testimony whereof I have hereunto set my name this 14th day of June, 1923.

C. WELLINGTON LEWIS.
